UNITED STATES PATENT OFFICE.

CHARLES H. IRWIN, OF WILMINGTON, OHIO.

AUGER-BIT.

SPECIFICATION forming part of Letters Patent No. 404,197, dated May 28, 1889.

Application filed October 20, 1887. Serial No. 252,935. (No model.)

To all whom it may concern:

Be it known that I, CHARLES H. IRWIN, a citizen of the United States, residing at Wilmington, in the county of Clinton, State of 5 Ohio, have invented certain Improvements in Auger-Bits, of which the following is a specification, reference being had to the accompanying drawings.

My invention is designed as an improvement upon the auger-bit shown and described in Letters Patent No. 361,522, granted to me on the 19th day of April, 1887, in order to render the operation thereof more secure and efficient.

15 In the accompanying drawings, Figure 1 is a view of the bit in a vertical position from the side on which the outlining-lip is located. Fig. 2 is a top view, and Fig. 3 is a view taken from the opposite side of the bit from that 20 shown in Fig. 1.

My invention consists in a solid center stem, B, around which is formed a convoluted blade, C, the latter terminating in a sharp-cutting floor-lip, b. The central stem, B, terminates 25 in the ordinary screw-point, E, as shown. Just below the screw portion of the stem I have provided a short convoluted blade, D, which preferably extends about half-way around the stem, as shown. This short blade terminates 30 in a floor-lip, b², and an outline-cutting lip, b', on the opposite side of the stem from the lip b. The body of the outline or spread lip b' preferably extends out beyond and beneath the lip b², as shown.

35 In use the lip b' cuts and outlines the hole to be bored, while the floor-lip b follows, lifting out the chips, the floor-lip b² being used only in case the lip b should become broken or disabled, as said latter lip is on a line 40 slightly elevated above lip b².

The object sought to be attained by having the outline-lip b' on the short blade is to steady the bit in its operation. As before stated, the lip b' cuts the outline of the hole, while the floor-lip b, on the opposite side the 45 stem, cuts and lifts the chips. The strains on the center stem are thus more or less equalized.

In case the lip b should from any cause become broken or disabled, the bit would still 50 be operative by the aid of the floor-lip b²; but in this case the strain would not be so equally divided.

The advantages of my improved bit have been set forth, and consist in the additional 55 means of security and for equalizing the strain on the center stem.

What I claim as new, and desire to secure by Letters Patent, is—

1. In a central-stem auger-bit, the central 60 stem, B, having a convoluted blade, C, terminating in a floor-lip, b, and a short convoluted blade, D, terminating in a floor-lip, b², and an outline-lip, b', the latter extending out beyond and below the floor-lip b², substantially 65 as set forth.

2. In a central-stem auger-bit, the central stem terminating in a screw-point and provided with a convoluted blade, C, terminating in a floor-lip, b, and a short convoluted blade, 70 D, terminating in a floor-lip, b², and an outline-cutting lip, b', the latter extending out beyond and below the floor-lip b², the cutting-edge of lip b being elevated above the lip b², substantially as set forth.

CHARLES H. IRWIN.
